J. P. GRAHAM

WALL HANGER FOR PLUMBING FIXTURES

Filed May 9, 1921

INVENTOR
James P. Graham.
BY *Wm. C. Brown*
ATTORNEY

UNITED STATES PATENT OFFICE.

JAMES P. GRAHAM, OF KANSAS CITY, MISSOURI.

WALL HANGER FOR PLUMBING FIXTURES.

Application filed May 9, 1921. Serial No. 467,836.

To all whom it may concern:

Be it known that I, JAMES P. GRAHAM, a citizen of the United States, residing at Kansas City, in the county of Jackson and State of Missouri, have invented certain new and useful Improvements in Wall Hangers for Plumbing Fixtures; and I do declare the following to be a full, clear, and exact description of the invention, such as will enable others skilled in the art to which it appertains to make and use the same, reference being had to the accompanying drawings, and to the figures of reference marked thereon, which form a part of this specification.

This invention relates to wall hangers for plumbing fixtures and the primary object thereof is to provide means for suspending a water closet or slop sink above the floor so that access may be had beneath the same for sweeping, mopping, etc. Wherever a plumbing fixture is supported by standards, the space in rear thereof is generally inaccessible so that dust, dirt and the like accumulate, which makes an unsanitary condition.

According to my invention means is provided for supporting the plumbing fixture above the floor so that this disadvantage will not be encountered.

The novel arrangement of my invention will be apparent by reference to the following description in connection with the accompanying drawings, in which—

Fig. 1 is a side elevational view of a plumbing fixture, a soil pipe and a bracket for supporting the fixture to the soil pipe.

Fig. 2 is a perspective view of the soil pipe and the hanger or bracket.

Fig. 3 is a detail perspective view of the soil pipe and bracket in spaced relation.

Fig. 4 is an elevation of a portion of a different type of soil pipe from that illustrated in Fig. 1 to which my invention is shown as applied.

Referring now to the drawings by numerals of reference:

1 and 2 designate spaced partitions between which may be provided a soil pipe 3, having at its upper end an L fitting 4, from which extends a vent pipe 5. The vertical face of the L is provided with an enlarged flange 6 surrounding the internal threads 7 to receive a nipple 8, connecting the discharge end 9 of the bowl 10. The flange 6 is shown as provided with a plurality of

spaced openings 11 to receive the machine bolts 12, which may pass through the elongated slots 13 in the bracket plate 14. The slots 13 are arranged in circular series about the nipple-receiving openings 15 in the plate 14 and they are elongated to accommodate for different adjustments; that is, the plate 14 may rotate upon the flange 6 to level the sides of the fixture to be mounted.

The bracket plate 14 is provided near its upper portion with stud bolts 16 and 17, the respective ends 18 and 19 of which are threaded into the plate 14 and the opposite ends 20 and 21 of which may project through the flange 22 on the rear end of the bowl 10 and receive nuts 23 so that the bowl may be fastened to the bracket plate.

The nipple 8 will be screwed into the collar 24 and into the threads 7 so that a tight connection may be made.

Extending outwardly from the lower portion of the bracket plate are jam bolts 26 and 27, which are threaded into the plate at the lower portion and which are provided with screw driver-receiving heads 28 so that they can be screwed into the plate 14, the heads 28 being provided with removable caps 29, which form stops against which the lower portion 30 of the bowl can project, the jam bolts serving as spacing elements and supports for the lower portion of the bowl. It will, therefore, be seen that the bowl can be conveniently supported above the floor in an inexpensive and convenient manner.

In Fig. 4 I have shown a vertical soil pipe 31 having a lateral branch 32 in which is a Y branch 33, provided with the L fitting 4 to which the plate 14 may be attached. In this instance the bolts 12 engage the slots designated 13' in the plate; thus, the plate is mounted in the vertical position as before described.

Various other types of fittings may be employed, it being obvious that the essential feature of my invention resides in providing a bracket adapted to be conveniently attached to a lifting so as to efficiently support a plumbing fixture above the floor so that access to the space below it may be readily had.

An important feature of the invention resides in the adjustability of the bracket plate 14, which, on account of the grouping of the slots 13, makes it possible to properly suspend the bowl irrespective of the an-

gle or position of the fitting to which it is attached.

What I claim and desire to secure by Letters Patent is:

- 5 1. Means for supporting a plumbing fixture above the floor, said means comprising a bracket plate having an opening there-through and bolt-receiving slots arranged in circular series about the opening, means for bolting the plumbing fixture to the plate, and stop means carried by the lower portion of the plate against which the lower portion of the plumbing fixture may abut.
- 10 2. Means for supporting a plumbing fixture above the floor, said means comprising a bracket plate having an opening there-through, the bolt-receiving slots arranged in circular series about the opening, means for bolting the plumbing fixture to the plate, and adjustable stop means carried by the lower portion of the plate against which the lower portion of the plumbing fixture may abut.
- 15
- 20

3. The combination with a soil pipe having an inlet, a flange surrounding the inlet, a bracket plate having an opening concentric with the inlet in the soil pipe and provided with elongated slots about the perimeter of the opening, bolts extending through the elongated slots and engaging openings in the flange of the soil pipe whereby the bracket plate can have angular adjustment and be secured in any adjusted position within the limits of the slots, a plumbing fixture, stud bolts engaging the bracket plate and the plumbing fixture to secure the two together, a nipple threaded in the inlet of the soil pipe and connecting it with the outlet of the plumbing fixture, and adjustable jam bolts carried by the bracket plate and having heads to bear against the plumbing fixture, the jam bolts being below the stud bolts and adapted to level the plumbing fixture.

In testimony whereof I affix my signature.

JAMES P. GRAHAM.
